P. Fasson

By *John Randolph, Jr. Atty.*

UNITED STATES PATENT OFFICE.

PATSY FASSON, OF MOUNT PLEASANT, PENNSYLVANIA.

SWORD.

1,371,881.

Specification of Letters Patent. Patented Mar. 15, 1921.

Application filed November 6, 1919. Serial No. 336,165.

To all whom it may concern:

Be it known that I, PATSY FASSON, a citizen of the United States, residing at Mount Pleasant, in the county of Westmoreland and State of Pennsylvania, have invented certain new and useful Improvements in Swords; and I do hereby declare the following to be a full, clear, and exact description of the invention, such as will enable others skilled in the art to which it appertains to make and use the same.

My invention relates to swords, its principal object being to provide a sword or other weapon in which the combat blade is telescopically associated with the handle and arranged so that the point thereof normally extends a short distance beyond the end of the handle, thus rendering it impossible for an opponent to gage the total length of the sword before the blade is extended for use.

A further object of the invention is to provide a telescopic sword which will project the blade thereof automatically as the sword is thrust toward the opponent.

Another object of the invention is to provide an improved splice bar, which can be effectively used for uniting broken rails and which will necessitate the cutting of two notches in the rail flange.

Still another object of the invention is to provide a sword which will not be cumbersome to carry and which will be protected against the weather.

Another object of the invention resides in the provision of a sword which includes an extensible blade that will be rigidly connected with the handle of the sword when in extended position.

An additional object of the invention is to provide a weapon having the above characteristics, which is simple in construction, consists of few parts, and may be manufactured inexpensively.

With the above and other objects in mind, the invention consists of the novel combination of elements, construction and arrangement, operation and specific features which will be hereinafter enlarged upon and recited in the sub-joined claims.

On the drawing attached hereto:

Figure 1 is a side elevation of the sword in retracted position;

Fig. 2 is a like view illustrating the combat blade in extended position;

Fig. 3 is a fragmentary view partly in section and partly in elevation;

Fig. 4 is a transverse sectional view taken on line 4—4 of Fig. 1;

Fig. 5 is an enlarged detail view illustrating 60 the latch for retaining the combat blade in retracted and projected positions, and

Fig. 6 is a modified embodiment of the invention as applied to a rifle.

Referring to the drawings in detail, 65 wherein like characters indicate corresponding parts in all the views, the numeral 5 denotes a sheath provided with a handle 6. Disposed within the sheath as its longitudinal edges are tubes 7 which stop short of 70 the outer end of the sheath.

Slidably mounted in the sheath 5 is a combat blade 8 which is normally disposed so that it will project out of the sheath for only a slight distance. The inner end of the 75 blade 8 is provided with a head 10 fitting snugly within the sheath and is provided with recesses 12 each of which is in alinement with one of the tubes 7. Parallel rods 13 extend rearwardly from the head 10, each 80 of which is disposed in one of the recesses 12 and project within the tube 7 and are adapted for longitudinal movement therein. Expansible coil springs 14 encircle the rods 13 and bear against the closed ends of the 85 tubes. The opposite ends of these springs are seated in the recesses 12 and bear against the head 10 to normally project the blade from the sheath.

A collar 15 is mounted upon the outer end 90 of the sheath 5 and is retained thereon by fastenings 16. When the blade is projected the head 10 engages the collar 15 to limit the outward movement of the blade. This collar is formed of relatively soft metal so 95 that the cutting edges of the blade will not become dulled by contacting therewith.

In order to retain the blade in projected and retracted positions there is provided a leaf spring 17 one end of which is fixed to 100 the inner face of the head 10 and is provided with a head or button 18 which is engageable in either of the openings 19 in the sheath 18 to lock the positions illustrated. The blade in the free end of this leaf spring 105 is bent to underlie the button and contacts with the adjacent wall of the tube.

A second leaf spring designated at 20 is provided which has one end disposed in a recess 21 in the block and is bent around the 110

block to frictionally contact with the sheath and retards the movement of the blade 8 after the same is released thereby preventing the same from becoming projected too violently.

It will be manifest that upon depressing the button 18 the coil springs 14 will project the blade from the sheath, the button 18 riding into the opening 19 at the forward end of the sheath. When it is desired to retract the blade the button 18 is depressed and the blade moved inwardly until the button or stud 18 engages in its opening at the front of the sheath.

15 A scabbard 26 is provided to protect the outer end of the blade and carries a resilient latch 27 for engagement with the blade to retain the scabbard thereon. The usual strap swivels 28 are provided for both the 20 scabbard and sheath.

In the modified embodiment of the invention illustrated in Fig. 6 the handle is omitted and the sheath constructed as a bayonet. In this construction the blade is entirely 25 housed within the sheath when in retracted position.

The construction illustrated and described are practical embodiments of the invention but it will be understood that the same may 30 be modified and altered in many respects, and that such limits of modification are only governed by what is claimed.

What is claimed is:—

1. In a weapon, a sheath, tubes in the 35 sheath, a combat blade slidably disposed in the sheath, parallel rearwardly extending rods also carried by the blade, each of which is received in one of the tubes, coil springs encircling the rods and normally urging the 40 blade from the sheath, a latch carried by the blade for engagement with sheath to retain the blade in retracted or projected position, and a friction element associated with the blade to slightly retard the thrust of the 45 same.

2. In a sword, a sheath, a combat blade slidably disposed in the sheath, a head carried by the inner end of the blade and snugly received in the sheath, the head being provided with recesses, tubes in the sheath in 50 alinement with the recesses in the head, rods secured in the recesses and slidably engaged in the tubes, expansible coil springs disposed within the tubes and encircling the rods and having one end engaged in the recesses and 55 normally urging the blade forwardly, and a latch for retaining the blade within the sheath and in extended position.

3. In a weapon, a sheath, tubes disposed in the sheath, a blade slidably mounted in 60 the sheath, a latch carried by the blade adapted to engage the sheath to retain the blade in either retracted or projected position, rods carried by the blade and slidably received in the tubes and expansible coil 65 springs encircling the rods and urging the blades from the sheath.

4. In a weapon, a sheath, a combat blade slidably mounted in the sheath, a head carried by one end of the blade, coil springs 70 arranged in the sheath and normally projecting the blade therefrom, and a leaf spring carried by the head and resiliently engaging the sheath to retard the movement of the blade when projected.

5. The combination with a hollow handle open at one end, and a blade slidably mounted therein, of parallel tubes in the handle, parallel rods carried by the rear end of the blade and slidably in the tubes, and expansible coil springs in the tubes and encircling the rods, and engaging the blade to project the same forwardly.

In testimony whereof I affix my signature in presence of two witnesses.

PATSY FASSON.

Witnesses:

MATTEO RUGGIERI,
STANLEY CROWE.

It is hereby certified that in Letters Patent No. 1,371,881, granted March 15, 1921, upon the application of Patsy Fasson, of Mount Pleasant, Pennsylvania, for an improvement in "Swords," an error appears in the printed specification requiring correction as follows: Page 1, strike out the paragraph beginning lines 26-30 inclusive; and that the said Letters Patent should be read with this correction therein that the same may conform to the record of the case in the Patent Office.

Signed and sealed this 3d day of May, A. D., 1921.

[SEAL.]

T. E. ROBERTSON,

Commissioner of Patents.
